THE BOSTONIAN

UNITED STATES PATENT OFFICE

JOSEPH BOROSTYAN, OF AKRON, OHIO, ASSIGNOR OF FORTY PER CENT TO JOSEPH KUNGLE, OF AKRON, OHIO

RAILWAY-SIGNAL MECHANISM

Application filed March 23, 1929. Serial No. 349,472.

This invention relates to certain new and useful improvements in railway signal mechanism and has for its primary object to give both audible and visual signals to the engineer of a train in the event of a railway switch being accidentally open and the train shifting to a siding rather than travelling on a straight line, while an audible signal is given in the switchman's house or tower so that proper provision can be made for stopping the train or switching the same onto the main line.

A further object of the invention is to provide a railway signal mechanism of the above type wherein the car or train is equipped with a novel construction of trolley pole arms adapted to be engaged with spaced wires disposed above the track siding for closing a circuit to give a signal in the car or train and in the switchman's house when the train has been accidentally switched from a main line to siding.

With the above and other objects in view that will become apparent as the nature of the invention is better understood, the same consists in the novel form, combination and arrangement of parts hereinafter more fully described, shown in the accompanying drawings and claimed.

In the drawings:—

Fig. 1 is a diagrammatic top plan view of a railway track structure showing a main line siding with the electrical signal mechanism located adjacent the track siding;

Figure 2 is a diagrammatic perspective view similar to Figure 1 showing visual and audible signals carried by a car;

Figure 3 is a fragmentary side elevational view of the car showing the switch arm or trolley pole extending upwardly therefrom;

Figure 4 is a detail sectional view taken on line 4—4 of Figure 3 showing the insulated mounting for the pole arm or switch;

Figure 5 is a detail sectional view taken on line 5—5 of Figure 3;

Figure 6 is an end elevational view of the pole arm, with a part of the car shown in section;

Figure 7 is a side elevational view of the upper end of the post and cross arm for sup-

porting the trolley or switch or line wires;

Figure 8 is an edge elevational view of the upper end of the post;

Figure 9 is an enlarged detail sectional view similar to Figure 8, showing the insulator for the line wire angularly depending to provide a guide and clearance for the trolley pole or switch arm carried by the car;

Figure 10 is a side elevational view, similar to Figure 6 of another form of trolley pole with the cars shown in section; and

Figure 11 is a vertical sectional view of the form of trolley pole mounting shown in Figure 10.

The signal mechanism may be associated with electric or steam railways and as diagrammatically illustrated in Figures 1 and 2, the reference numeral 1 designates a main track, while a track siding is indicated by the reference numeral 2, the track switch being shown at 3. The mechanism adapted for giving a signal in a car of rolling stock and also in a switchman's house is associated with the sliding 2, the signal mechanism being rendered operable should the switch 3 be accidentally thrown to cause the rolling stock to pass onto the siding 2.

As diagrammatically illustrated in Figures 1 and 2, the signalling mechanism is of an electrical character and comprises a wire *a* leading from a source of energy to the switchman's house *b* and connected to one terminal of an audible signal *c*. The wire *d* leading from the terminal is supported on the cross arm *e* of the post *f* that is set adjacent the siding 2, the wire *d* continuing as an elevated trolley wire *g* and terminating at an insulated connection *h* on the cross arm *i* of the post *j*. The other wire *k* from the source of energy is connected to the other terminal of the audible signal *c* and continuous as at *m* to the cross arm *e* of the post *f* to run parallel with the wire *g* as at *n*, the insulated terminal *o* thereof upon the arm *i* of the post *j* continuing downwardly as at *p* to be grounded on the siding 2.

The signal mechanism within the car 4 shown in Figure 3 is both visual and audible and includes a trolley pole arm 5 having an insulated mounting on the car 4 to be later

described which mounting is connected to wire *g* attached to one terminal of the bell *r*. The wire *s* attached to the other terminal of the bell *r* leads to the lamp *t* and continues at 5 *u* to the ground through the car axle 6.

When the car moves onto the siding 2, the arm 5 engages the trolley line or wires *g* and *n* to bridge them for closing the circuit for the wires *a* and *b* to operate the signal *c* in the switchman's house *b*. Current flows from the arm 5 through the wiring of the car 4 to operate the bell *r* and lamp *t*, the car wiring being grounded at 6 and returning through the wire *d* through the trolley wire *n*. In this way, the 10 operator or engineer of the car is warned that he has left the main line and is on a siding, while a similar signal is given the switchman of the house *b* and proper steps can be taken 15 either to stop the car or reswitch the same onto the main line 1.

As shown in Figures 3 to 6, the arm 5 is insulated from the car 4 as at 7, the insulated side extension 8 of the arm 5 having the wire *g* leading therefrom to the signal mechanism.

The insulator mounting on the post arms *e* and *i* for the trolley lines *g* and *n* are shown in Figures 7 to 9, each wire *g* and *n* passing through an insulator 8 of depending angular formation to permit the arm 5 to be guided onto the wires *g* and *n*. The upper end of the arm 5 is laterally directed to form a horizontal extension 9 with an upstanding rib 10 intermediate the ends thereof providing side pockets 11 for the wires *g* and *n* as shown in 25 Figure 6.

Another form of trolley arm is illustrated in Figures 10 and 11 and includes a cylinder 12 carried by a mounting plate 13 adapted to be attached to the car floor and insulated therefrom, the cylinder 12 receiving a rod 14 having a collar 15 fixed thereto, within the cylinder. A coil spring 16 in the cylinder 12 surrounds the rod 14, abutting at its upper end the collar 15 and being engaged at its lower 30 end by the screw plug 17 threaded into the lower end of the cylinder 12, the screw plug 17 having an axial opening 18 for the passage of the rod 14 when the latter is compressed. The upper end of the rod 14 constitutes a trolley pole head 9^a of the character shown and described in connection with Figure 6. The 35 spring mounting for the rod 14 maintains engagement thereof of both the trolley lines *g* and *n*.

While there are herein shown and described the preferred embodiments of the present invention, it is nevertheless to be understood that minor changes may be made therein without departing from the spirit and scope 40 of the invention as claimed.

I claim:

1. In a switch arm mounting of the type described, an arm, a spring support therefor constructed and adapted to be attached to the side 45 of a car and a horizontal lateral extension on

the upper end of the arm having spaced seats for trolley line circuit wires, said seats being depressed and separated by an intervening ridge, and said arm being adapted to be located above and extending laterally of its supporting vehicle.

2. In a switch arm mounting of the type described and as claimed in claim 1, a cylinder, an arm slideable in the cylinder, and a spring in the cylinder engaged with the arm for tensioning the same in an upward direction.

3. In a switch arm mounting of the type described and as claimed in claim 1, a cylinder, an arm slideable in the cylinder, a collar fixed to the arm within the cylinder, an apertured screw plug in the lower end of the cylinder through which the arm extends, and a coil spring surrounding the arm between the collar and plug.

In testimony whereof I affix my signature.

JOSEPH BOROSTYAN.
